ABRADING NIB FOR ABRADING MACHINES

Filed Jan. 31, 1927

INVENTOR.
Ferdinand J. Hohnhorst
By H. T. Neffle,
His Attorney.

UNITED STATES PATENT OFFICE.

FERDINAND J. HOHNHORST, OF COVINGTON, KENTUCKY.

ABRADING NIB FOR ABRADING MACHINES.

Application filed January 31, 1927. Serial No. 164,831.

The present invention relates to abrading nibs employable for roughing grinding wheels, such as emery wheels employed in grinding or polishing the surfaces of metal 5 in precision grinding.

It is the object of the invention to provide a novel abrading part arranged to have rotation imparted thereto by contact with the rotating grinding wheel; further, 10 to provide a rotary abrading nib of novel construction arranged for end-contact between said nib and the grinding surface of the grinding wheel; further, to provide a rotary abrading part arranged for endwise 15 presentation to the grinding wheel and provided with endwise holes for forming cutting edges acting on the grinding surface of the grinding wheel with a roughing effect for reducing the same rapidly to cylindrical 20 form, or rapidly reducing all parts of the grinding surface of the grinding wheel to the desired form.

The invention will be further readily understood from the following description and 25 claims, and from the drawings, in which latter:

Fig. 1 is an axial section of my improved device, taken on the line 1—1 of Fig. 2, showing the same mounted in an abrading 30 machine.

Fig. 2 is a side elevation of the same.

Fig. 3 is an end elevation of my improved device.

Fig. 4 is an axial section of the same, 35 taken on the line 4—4 of Fig. 3.

Fig. 5 is an axial section of the same, taken on the line 5—5 of Fig. 3.

The invention is exemplified as used in a usual grinding or polishing machine for effecting grinding or polishing upon the work, for instance, in precision grinding. 40 In machines of this character it is necessary to frequently refinish the grinding surface of the grinding wheel, as this grinding surface during use becomes dull or out of true or needs refinishing for other reasons. When refinishing the grinding surface it is frequently necessary to reshape the grinding wheel to restore its proper cylindrical or 45 other form, and to give the grinding surface what is known as a roughing cut. The grinding surface is thereafter trued or finished in suitable manner.

The object of the present invention is to 50 provide novel means for producing such

roughing cut in quick, accurate and convenient manner, and preferably while the rotary grinding wheel is retained in its position and driving relation in the grinding or polishing machine. Such machinery is usually provided with means for causing reciprocation of the work in opposite directions across the grinding wheel having a stationary position, or to cause reciprocations of the grinding wheel in opposite directions lengthwise of the work which has a stationary position.

It may be instanced in the present exemplification that the grinding wheel 11 is stationarily positioned but adjustable with relation to the work, and that the work is suitably supported and caused to rotate upon a table 12, which has reciprocations imparted thereto in suitable manner in opposite directions, so as to move the work lengthwise in opposite directions with relation to the grinding surface of the rotating grinding wheel.

The rotary abrading part which coacts with the grinding surface for roughing the same is instanced as a nib, stub or pencil, and is hereinafter referred to as a nib, and is shown at 15. It is presented endwise toward the abrading wheel. It is preferably normally quiescent, and has rotation imparted thereto by the rotating grinding wheel. It may be of suitable material and may for instance be a casting of metal for instance iron or steel or be of other material suitably shaped.

As exemplified, it comprises an abrading wall 16 presented endwise to the grinding surface to be roughened. It is preferably rotated by contact of the grinding surface of the rotating grinding wheel with the end of said wall.

This end-contact preferably takes place at one side of the axis of rotation of the abrading nib, and the abrading nib is presented to the grinding surface with its axis of rotation at an angle to a plane perpendicular to the axis of rotation of the grinding wheel and preferably also tangential to a circle having the axis of rotation of the grinding wheel as a center.

The rotary abrading nib is shown mounted in a chuck 17, rotatably supported in suitable manner on a spindle 18, journaled in a fixture 19, as in ball bearings 20, 21, the fixture being suitably secured, releasably

or otherwise, to the reciprocating work table 12 or a part mounted thereon.

A fly-wheel effect is preferably imparted to the rotary abrading nib for maintaining, 5 equalizing and emphasizing the rotations imparted thereto by the rotating grinding wheel. This fly-wheel effect is in the present instance produced by a fly-wheel 22 fixed to the spindle 18.

10 The chuck is exemplified as having a socket whose lateral wall is tapered and contracts toward its inner end. The rotary abrading nib is provided with a part or shank arranged to be received in the chuck, 15 shown as a shank 23, whose outer periphery is tapered complementary to the tapered socket of the chuck, for being clampingly received in said chuck for fixing the rotary abrading part to the chuck and positioning 20 the same axially with relation thereto.

This tapered outer periphery of the shank 23 may be on a collar 24 fixed about the body portion of the shank, as by means of an annular tongue and groove connection 25.

25 This is advisable when the nature of the material of the body of the nib is such as not to adhere frictionally sufficiently or to adhere too much to the complementary wall of the socket. For instance, if the body of the 30 nib is formed out of hard metal, for instance, chilled cast iron, it is advisable to provide it with a collar of softer material, for instance, Babbitt metal.

The rotary abrading nib is provided with 35 an axial bore 31 about which the abrasive wall 16 is located. This bore preferably extends axially through the rotary abrading nib. One of the objects of providing the axial bore is to remove the material along 40 and adjacent to the axis of rotation of the rotary abrading nib, this axis being a neutral or non-rotating line. The presence of abrasive material at and adjacent to said line might be less responsive to the abrasive 45 action between the rotary abrading nib and the grinding wheel and form a point or portion at said axis which would have a tendency to gouge into or form detrimental marks or scores in the grinding surface of 50 the grinding wheel being treated, and to avoid which the axial bore is provided.

This axial bore preferably extends through the abrading nib and the holding shank of the nib, as for the insertion of a 55 tool for ready removal of the rotary abrading nib from the chuck, which may act by leverage, compression or otherwise between the inner end of the nib and the bottom of the chuck.

60 The end-contact face 16 of the rotary abrading nib is preferably frusto-conical in form. The angular presentation of the axis of rotation of the endwise presented nib with relation to the grinding surfaces of 65 the grinding wheel maintains such frusto-

conical form upon the end-contact face of the abrading nib.

This end-contact face is provided with holes 32, 33, for forming cutting edges 34, 35, in said abrading face. These cutting 70 edges act with a swirling motion upon the grinding face. The holes are preferably located at different distances from the axis of rotation of the rotary abrading nib, and they have paths of different diameters about 75 said axis. The speeds of the cutting edges across a given portion of the grinding surface increase with the distance from said axis of rotation, and portions of the cutting edge at each hole, at the respective sides of 80 the circular path of the center of the hole, act progressively upon the grinding surface, whereby said cutting edges act with swirling movements upon said grinding surface, for producing quick and accurate cutting and 85 roughing of the grinding surface.

These holes preferably extend lengthwise of the axis of rotation of the rotary abrading nib. The holes more distant from the axis of rotation of the nib are also preferably of greater diameter, the diameters of the holes decreasing as they approach said axis. The holes at the inner periphery of the abrading wheel are shown as merging 90 with the axial bore of the nib, as at 36, and the sides of the holes adjacent to the outer periphery of said abrading wheel are shown at 37 as open at said outer periphery. The bore and the holes may be formed when casting the body of the nib, if a casting is 95 employed.

Having thus fully described my invention, what I claim as new, and desire to secure by Letters Patent, is:

1. A rotatable abrading nib for coaction 105 with the grinding face of a grinding wheel, said rotatable abrading nib having an end-contact abrading face and holes in said end-contact abrading face at different radial distances from the axis of rotation of said rotatable abrading nib movable in circles of different diameters across said grinding face of the grinding wheel. 110

2. A rotatable abrading nib for coaction 115 with the grinding face of a grinding wheel, said rotatable abrading nib having an end-contact abrading face and holes of different diameters in said end-contact abrading face at different radial distances from the axis of rotation of said rotatable abrading nib for moving in circles of different diameters across said grinding face, said holes decreasing in diameter toward said axis of rotation. 120

3. A rotatable abrading nib for coaction 125 with the grinding face of a grinding wheel, said rotatable nib having an end contact abrading face arranged about the axis of rotation of said abrading nib and provided with holes extending lengthwise of said axis for forming abrading walls having abrasive 130

action on said grinding face and moving in circular paths of different diameters across said grinding face.

4. A rotatable abrading nib for coaction with the grinding face of a grinding wheel, said rotatable abrading nib having an axial bore and an abrading wall surrounding said bore extending lengthwise of said axis and having a conical end-contact abrading face, 10 and said wall provided with holes whose walls form cutting edges in said conical end-contact abrading face for abrasive action on said grinding face in a path at one side of said axis.
- 15 5. A rotatable abrading nib for coaction with the grinding face of a grinding wheel, said rotatable abrading nib having an axial bore and an abrading wall surrounding said bore extending lengthwise of said axis and 20 having an end-contact abrading face, said wall provided with holes extending lengthwise of said axis at various distances from

said axis with inner ones of said holes merging with said bore, and the outer ends of the walls of said holes forming cutting edges 25 in said end-contact abrading face for abrasive action on said grinding face.

6. A rotatable abrading nib for coaction with the grinding face of a grinding wheel, 30 said rotatable abrading nib having an end-contact abrading wall at one end and a stem at its other end for reception in a chuck having a nib-releasing part, said end-contact wall provided with holes the walls of which 35 form cutting edges in said end-contact abrading face, and said rotatable abrading nib provided with an axial bore for reception of a tool past said end-contact abrading wall and said cutting edges for coaction with said nib-releasing part through said 40 bore for release of said nib.

In testimony whereof, I have hereunto signed my name.

FERDINAND J. HOHNHORST.
